PAGE 2

Fig. 3

FIGURE 1 is a perspective view of a tool for use in taping freshly cemented carpet seams and the like embodying my new design.

FIGURE 2 is a side elevation thereof with the opposite side having the same appearance.

FIGURE 3 is a plan view of same.

The dominant features of my design reside in the portions shown in full lines.

I claim:

The ornamental design for a tool for use in taping freshly cemented carpet seams and the like, substantially as shown and described.
